[57] **CLAIM**

The ornamental design for an operatory module for a health treatment facility, as shown and described.

DESCRIPTION

FIG. 1 is a front elevational view of an operatory module for a health treatment facility, showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a front perspective view thereof;

FIG. 7 is a front elevational view of a second embodiment of an operatory module for a health treatment facility;

FIG. 8 is a top plan view thereof; and

FIG. 9 is a rear elevational view thereof.

FIG. 1

FIG. 2

FIG. 3

FIG. 4

FIG. 5

FIG. 6

FIG. 7

FIG. 8

FIG. 9
